DOOR CHECK

Ewald Loehr and Edward G. Sprink,
Milwaukee, Wis.

Application July 26, 1946, Serial No. 636,512

3 Claims. (Cl. 292—178)

1

This invention relates to a door check which may be permanently attached to any door with bolts or metal screws or other type fastenings, and it is claimed that this door check will positively hold the door at any desired position without the need of a strike plate in the floor. Instead of the latter a rubber roller is provided at the bottom end of a foot-operated rod as pedal for compressing the roller against the floor with the door in any desired position, closed or open.

One embodiment of the invention is illustrated in the accompanying drawings, wherein like reference numerals relate to the same details in the different views.

Figure 1 is a side elevational view of the door stop as attached on a door;

Figure 2 is a front elevation and part section of Figure 1;

Figure 3 is an assembled view in front elevation of the actuating rod with cap;

Figure 4 is a top plan view of Figure 3;

Figures 5 and 6 are a top plan view and a front elevation respectively of an arresting plate for the actuating rod;

Figures 7 and 8 are a top plan view and a front elevation respectively of a lifting spring washer;

Figures 9, 10 and 11 respectively are a side elevation, front elevation and top plan view of the yoke for the roller, and

Figures 12 and 13 respectively are a front view and side elevation of the check roller.

In the drawings reference numeral 20 in general indicates the casing in which all the elements of the door check are enclosed. This casing is preferably a metal stamping with a flat rear wall 19 intended for attachment to the face of a door 21 by means of screws 22. The main portion 23 of the casing consists of a hollow, thin walled shell, wide open at the bottom as at 24 and closed at the top except for a round opening 25 for the actuating rod 26 to go through. Above this top the rear wall 19 extends upwardly to provide a small pocket 27 with a narrow slit 28 on the front side for receiving a lip 28 of a friction plate 29 permitting a limited up and down oscillation of the plate. This plate 29 is tilted upwardly by means of a compression spring 30 so that the actuating rod 26 passing through the round opening 25 in the plate and the corresponding opening 25 in the top wall of the casing shell 23, will become locked in position.

The actuating rod 26 has a straight shank 32 with a cap 33 threaded thereon at its upper

2

end, while a brake-shoe 34 is welded to its lower end. This shoe 34 consists of flat wings in the shape of an inverted V to form an angular seat for the top surface of the friction roller 35. The wings of the brake-shoe are square cut and may have side lugs 48 to prevent the shoe with the rod 26 from turning in the casing 23 to make sure that the periphery of the roller is in the direction of swing of the door. The roller is made of resilient rubber or similar material and has a metal bushing for a steel pin 37 on which it revolves in the two armed yoke 38.

Before putting the roller 35 in place between the arms of the yoke 38 a centering coil spring 15 39 is slipped on the shank 32 of the rod 26, and over the spring the top 45 of the yoke 38 having a hole 45a rides on said spring. Thereupon the roller 35 is put in place by pushing it up against the brake-shoe 34, and the pressure of 20 spring 39, and the pin 37 inserted through the bushing 36 into the bearings in the arms of the yoke 38.

About midway up in the shell 40 is provided a horizontal partition or shelf 41 having a round 25 opening 42 in axial alignment with the hole 25 in the top 54 of the shell 40. The rear wall 19 of this shell is preferably open to permit the placing of a lifting spring 43 and a cup washer 44 in readiness for inserting the actuating rod 30 26 into the casing to receive the stop pin 50 which will be held by the flange of the cup washer 44.

With the yoke 38, roller 35 and the spring 39 assembled on the actuating rod 26 as described, 35 the latter is now pushed up through the bottom opening of the casing 23, entering the hole 42 in the shelf 41 ready to receive the spring 43 and the washers 44. With these actuating elements 43, 44 pushed down on the rod 26 an 40 abutment pin 50 is pushed transversely through a hole in said rod. The spring 43 will then push the free upper end of the rod 26 through the free fitting top opening 25, the spring 30 causing the free edge of the friction plate 29 to swing up above the top of the casing, as seen in Figures 1 and 2.

Lastly the cap nut 33 is screwed on the end 50 of the rod 26 and the door check is then ready for attachment on the side of a door by screws 22, two of which engaging the side ears 52 on the casing 23 and a third goes through the rear wall extension 53 above the top 54 of the casing 23.

With the device thus attached on the door 55 21, the relative positions of the parts will be as

appear in Figures 1 and 2 with the actuating rod 26 raised to its inactive or top position by lifting spring 43, when the cupped washer 44 is stopped by the pin 50. The washer in turn reciprocates by preventing the pin from falling out by contacting the ends of said pin with its rim.

The roller 35 now merely touches the floor or stands lifted enough above the same to permit swinging the door open.

As soon as the operator has opened the door to the extent he desires, he will press down with his foot on the head cap 33 and the rod 26, thereby compressing the rubber roller by the brake-shoe 34 to get a firm hold on the floor.

Upon removing the foot from the cap 33, the roller will still remain compressed because the rod 26 is gripped fast by the friction plate 29, which stands at an incline to the axis of rod 26 to hold the latter firmly by engaging the surface of rod 26 with its opposite edges of the hole 31.

In order, lastly to release the holding action of the roller 35 on the floor, all that is needed is to press down the outer or free edge of the friction plate 29, when the rod with the roller will rush up through the action of lifting spring 43.

All metal parts in this case except screws, springs and actuating rod are produced by metal stamping.

It is to be understood that the invention as herein disclosed may be varied from the details described and shown, without departure from the spirit of the subjoined claims.

We claim:

1. A door check comprising an upright casting in the form of a shell open at the bottom and closed at the top and having a central partition between its ends; a push rod mounted for axial displacement in guide openings furnished in said top and in said central partition, the rod having a portion of its upper end projecting beyond said top, means for yieldingly urging the rod upwardly, a stop limiting the upward movement of the rod, exteriorly located means for arresting upward movement of the rod, a compressible element connected with the lower end of the rod and projecting beyond the open bottom of the shell for contact with the

floor comprising a roller, a yoke carrying the roller and slidably connected with the rod, yieldable means connected between the yoke and the rod and normally urging the yoke and roller upwardly, and a brake-shoe carried upon the lower end of the rod and having yielding contact with the periphery of the roller.

2. A door check comprising an upright casting in the form of a shell open at the bottom and closed at the top and having a central partition between its ends, a push rod mounted for axial displacement in guide openings furnished in said top and in said central partition, means for yieldingly urging the rod upwardly beyond said top, a stop limiting the upward movement of the rod, exteriorly located means for arresting the upward movement of the rod, a yoke slidably mounted upon the lower end of the rod and having downwardly extending side arm portions, a yieldable roller rotatably supported between the side arm portions of the yoke and projecting downwardly through said opening for contact with an underlying surface, a brake-shoe comprising an arched member secured to the lower end of the rod, and a spring means carried by the rod and interposed between the shoe and the top part of the yoke.

3. A door stop of the character stated in claim 2, wherein said shoe has laterally projecting ears extending beyond the sides of the side portions of the yoke and adapted to contact the adjacent walls of the shell for maintaining the roller against turning movement about the axis of the rod.
